UNITED STATES PATENT OFFICE.

LEO STEIN, OF ROCHESTER, NEW YORK.

DESIGN FOR A BURIAL-CASKET LID.

SPECIFICATION forming part of Design No. 19,469, dated December 3, 1889.

Application filed November 11, 1889. Serial No. 329,937. Term of patent 14 years.

To all whom it may concern:

Be it known that I, LEO STEIN, a citizen of the United States, residing at Rochester, in the county of Monroe and State of New York, 5 have invented and produced a new and original Design for Burial-Casket Lids, of which the following is the specification, reference being had to the accompanying drawings, forming a part thereof.

Figure 1 is a plan view of the burial-casket lid, showing my design; and Fig. 2 is a sectional view taken on line $x-x$, Fig. 1, illustrating the contour of the parts thereof, these two views being deemed necessary to fully 15 illustrate my design.

The leading features of my design consist in a central panel for the lid, said panel being composed of a central flat surface and a bordering rounded surface leading from said flat 20 surface, a cross-bar for dividing the lid into head and foot sections, and a molding raised above the plane of said panel.

The panel a of my burial-casket lid is formed with the flat central portion or surface 25 a' , and the bordering surface a^2 , of rounding contour, extending outwardly from said flat surface a' , thus presenting a pleasing and novel effect in the combining of the flat and rounding surfaces. Raised above the plane

of the panel a is a bordering molding b , which 30 presents an additional feature of pleasing appearance and novel effect. Arranged between the two extremities of the panel a is a cross-bar c , which divides the same into head and foot sections and is raised above the plane of 35 the panel a , thus breaking the monotony of the said panel and greatly adding to the general appearance and effect of the casket-lid.

Having thus fully described my invention, what I claim as new, and desire to secure by 40 Letters Patent, is—

The design for a burial-casket lid herein shown and described, the same consisting of a flat surface or panel, a bordering molding raised above the plane of said flat surface or 45 panel, rounding surfaces between said flat surface or panel and bordering molding, and a cross-bar dividing the lid into head and foot sections, substantially as set forth.

In testimony whereof I have hereunto signed 50 my name, in the presence of two attesting witnesses, at Rochester, in the county of Monroe, in the State of New York, this 7th day of November, 1889.

LEO STEIN.
